DESIGN FOR A FOLDING SHOE HORN

Alexander W. Forman, Chicago, Ill.

Application October 30, 1944, Serial No. 116,055

Term of patent 14 years

(Cl. D86—10)

To all whom it may concern:

Be it known that I, Alexander W. Forman, a citizen of the United States, residing at Chicago in the county of Cook and State of Illinois, have invented a new, original, and ornamental Design for a Folding Shoe Horn, of which the following is a specification, reference being had to the accompanying drawing, forming part thereof.

Fig. 1 is a front elevational view of a shoe horn provided with a folding handle and in open position, showing my new design, and Fig. 2 is a side elevational view thereof.

Fig. 3 is a front elevational view of a shoe horn provided with a folding handle and in closed position showing my new design, and Figs. 4 and 5 are side elevational and plan views thereof respectively.

I claim:

The ornamental design for a folding shoe horn, substantially as shown and described.

ALEXANDER W. FORMAN.
